John Burgess Troy, N.Y.
Letter Patent No. 175, dated 11th, April 1848

The Schedule referred to in these Letters Patent
and marking part of the same

to all whom it may concern:

Be it known that I, John Burgess of
the City of Troy, County of Rensselaer and State of New York
have invented and produced a new design for stoves, and that
the following, is a full and exact description reference being
had to the accompanying drawings making a part of this
specification.

The design is intended for the side, front and back
plate of a looking stove represented in the drawings as Fig. 1st
Front, Fig. 2nd Back and Fig. 3rd Side. These plates are orna-
mented with rosettes, scrolls, leaf & fancy borders reference being
had to the drawings. The panels of the side and door
attached in Fig. 3rd is depressed, & surrounded with a curved
and edged moulding as seen by the model and drawings.

I claim as my invention
and desire to secure by letters Patent the above
design consisting of the ornaments A & B in Fig.
3rd & C & D in Fig. 1st in connection with the ornaments
on the other plates as combined in the drawings.
